UNITED STATES PATENT OFFICE.

FREDERICK B. MALLORY, OF PORTLAND, OREGON.

DESIGN FOR A BLOCK SIDE.

44,612.

Specification for Design.

Patented Sept. 2, 1913.

Application filed May 22, 1912. Serial No. 699,076. Term of patent 7 years.

To all whom it may concern:

Be it known that I, FREDERICK B. MALLORY, a citizen of the United States, residing at Portland, in the county of Multnomah and State of Oregon, have invented a new, original, and ornamental Design for Block Sides, of which the following is a specification, reference being had to the accompanying drawing, forming part thereof, in which—

Figure 1 is a front view of my invention; Fig. 2 is a side elevation of same, and Fig. 3 is the reverse side of Fig. 1.

The lines A A represent openings through the web portions of my design.

What I claim is—

The ornamental design for a block-side as shown and described.

In testimony whereof I hereunto affix my signature in the presence of two witnesses.

F. B. MALLORY.
